UNITED STATES PATENT OFFICE.

CARL S. PASSAMANECK AND HARVEY E. McCARLOU, OF FULLERTON, CALIFORNIA.

RUNNING-TIME INDICATOR.

Application filed May 5, 1925. Serial No. 28,175.

To all whom it may concern:

Be it known that we, CARL S. PASSAMANECK and HARVEY E. McCARLOU, citizens of the United States, residing at Fullerton, in the county of Orange and State of California, have invented certain new and useful Improvements in Running-Time Indicators, of which the following is a specification, reference being had to the accompanying drawings.

This invention relates to running time indicators and more particularly to a device of this character especially adapted for use in conjunction with the motors of aeroplanes.

An important object of the invention is to provide a device of this character operated from a clock in combination with the revolution counter or tachometer of the aeroplane and in which the number of working parts is reduced to a minimum so that the strain placed upon the clock may be correspondingly reduced and slowing down of the clock is thus prevented.

A still further object of the invention is to provide in combination with a device having clock operated timing mechanism which is thrown into operation by a governor a construction such that the governor is prevented from transmitting strain or pressure to the clock shaft and so prevented from interfering with the accuracy of the clock.

A still further object of the invention is to provide a device of this character which may be readily and cheaply produced and installed.

These and other objects we attain by the construction shown in the accompanying drawings, wherein for the purpose of illustration is shown a preferred embodiment of our invention and wherein:—

Figure 1 is a side elevation partially in section of running time indicators constructed in accordance with our invention;

Figure 2 is a section on the line 2—2 of Figure 1;

Figure 3 is a section on the line 3—3 of Figure 1; and

Figure 4 is a detailed view partially in section showing the counter wheel shafts removed.

Referring now more particularly to the drawings, the numeral 10 indicates a U-shaped frame of which the bight portion is indicated at 11 and the arms 12 and 13.

From the bight portion 11 is supported a bracket 14 having a pair of depending arms 15 providing bearings for a drive shaft 16 operated in any suitable manner from the engine of a plane (not herein shown). Depending directly from and secured to the bight portion 11 are a pair of supports 17 and 18. In the support 18 and in the arm 13 of the U-shaped frame is journaled a shaft 19 collared, as at 20, to prevent longitudinal shifting thereof. This shaft has secured thereto a bevel gear 21 meshing with a bevel gear 22 carried by the shaft 16.

To the shaft 19 intermediate the supports 17 and 18 is secured one end member 23 of a spring arm flyball governor and to this end member one end of each of the spring arms 24 of the governor is secured. The opposite ends of the arms are secured to a second end bearing 25 carried by a shaft 26 coaxial with the shaft 19 and journaled in the support 17. The inner end of this shaft has a socket 27 receiving the end of the shaft 19 and the distance through which the shaft may enter in this socket is positively limited in any suitable manner as by a flange 28 formed on the shaft 19. The free end of the shaft 26 has formed therein a conical socket or center dip 29 which receives a stub center 30 carried by an arm 31 pivoted to the support 17, as at 32.

Supported from the arm 13 and paralleling the arms 12 and 13 are frame members 33 and 34. Journaled in the arm 13 and frame member 34 is a shaft 35 collared, as at 36, to prevent longitudinal movement thereof and adapted to be driven from a clock 37. The inner end of this shaft which terminates between the supports 33 and 34 has secured thereto a crown gear 38, the teeth of which are pointed. Slidably mounted in the support 33 in axial alignment with the shaft 36 is a support 39, the inner end of which is circular in cross section and provided with spaced stops 40 and 41 between which a sleeve 42 is mounted for rotation about the support. This sleeve has secured thereto a crown gear 43 for coaction with the crown gear 38 and combining therewith to provide a clutch connecting the shaft 35 with mechanism hereinafter to be described. This connection is accomplished through the medium of a gear wheel 44 which is likewise carried by the sleeve. The outer end of the support 39 is connected with the free

end of the arm 31 by a link 45 and the arm 31 adjacent its free end is connected with the frame member 33 by a light spring 46.

It will be seen that when the shaft 16 is 5 driven, this drive is transmitted to the shaft 19 and from this shaft to the governor, the flyballs of which may shift the movable element through but a limited distance. This shifting of the governor will permit a corresponding shifting of the arm 31 and this shifting is accomplished by the spring 46. The amount of shifting permitted is just sufficient to permit the teeth of the crown gears 38 and 43 to properly engage without placing any end thrust upon the shaft 17 so that all end thrust is held from the clock and any tendency to slow down the same as the speed of rotation increases due to such thrust will be eliminated.

20 Journaled in the arm 13 adjacent the end thereof is a shaft 47, the outer end of which is provided with a hand wheel 48 by means of which it may be rotated and the inner end of which is hollow, as at 49, and has mounted thereupon a flange 50, the inner face of which is roughened. Coaxial with and journaled at one end in the socket 49 and at the opposite end in a bracket 51 is a number wheel shaft 52 having at the end thereof 25 journaled in the shaft 47 a flange 53 for engagement with the flange 50 to serve as the clutch of a resetting mechanism. Coaxial with the shafts 47, 52, and journaled at one end in the arm 12, as at 54, is a second number wheel shaft 55, the opposite end of which is socketed for the reception of the inner end of the shaft 52, as indicated at 56. The shaft 55 is held against longitudinal movement by collars 57 and has within the 30 socket thereof a spring 58 which engages the contained end of the shaft 52 and urges the shaft toward the arm 13. Movement of the shaft 52 toward the arm 13 is limited by a suitable means, as at 59. Adjacent the shafts 40 52, 55, a trip supporting rod 60 has its ends secured to the arms 12 and 13, this rod paralleling the shafts 52, 55, and having arranged thereon groups of carrying-over wheels 61 and 62 corresponding to number 50 wheel groups 63 and 64 carried by the shafts 52 and 55 respectively. The ends of the supports 33, 34, extend adjacent the support 60 and have mounted therein a stationary shaft 65 upon which is mounted for 55 rotation a sleeve 66 having secured thereto a gear 67 and a second gear 68 operatively connected to the number wheels 63 and 64 respectively. The gear 67 meshes with the gear 44 of the sleeve 42 hereinbefore described and is of sufficient width to maintain mesh therebetween at all times during shifting of this sleeve as the clutch 38, 43, is engaged and disengaged. This gear 67 also meshes with the gear 69 rotatably mounted upon the rod 60 and this gear 69 in

turn meshes with the gear 70 secured to the shaft 52. The gear train 44, 67, 69 and 70 is but a transmission train and no change in speed of rotation occurs so that the shaft 52 is rotated at the same speed as the shaft 35 or through one rotation for each hour.

The operation of the device is substantially as follows: Assuming that the clutch 38, 43, is engaged and the clock 37 in operation, the shaft 52 is being continuously driven. Of the number wheels carried by this shaft, the right hand number wheel 71 is fixed on the shaft and has its periphery provided with subdivisions of an hour, expressed in minutes. At each rotation of the shaft, the next succeeding number wheel is operated in the usual manner through the carrying-over device connecting the two number wheels. Of the group 64, all of the number wheels are graduated in hours and since the carrying-over gear 68 is employed and engages the carrying-over device 62 connected with the first number wheel at each hour, the first number wheel will be advanced and as this advance continues, it will be transmitted to the remaining number wheels of the shaft 55. In performing the engagement for the drive, particular attention is directed to the fact that no pressure generated by the governor can be in any way transmitted to the clock shaft 35 and attention is further directed to the fact that this clock shaft comprises only that mechanism necessary for its connection to the number wheel shafts. The number wheels of the right hand shaft 52 are intended for recording the number of flying hours between times when the motor is overhauled while the number wheels of the shaft 55 give the total of flying hours for the life of the engine. At each overhauling, the number wheels of the shaft 52 are reset to zero, this being accomplished by forcing the shaft 47 inwardly to engage the disks 50, 53, and in rotating the shaft 47 through its hand wheel 48. This forcing of the shaft inwardly will disengage the gears 69 and 70 so that only the number wheels of the group 63 are reset.

It will be obvious that the structure hereinbefore set forth is capable of a considerable range of change and modification without materially departing from the spirit of our invention and we accordingly do not limit ourselves to such specific structure except as hereinafter claimed.

We claim:

1. In means for indicating the running time of motors or the like, a register, a clock, a shaft operated from the clock, a governor connectible with the motor to be operated therefrom and including a part shifted in one direction as the governor comes to rest, a non-rotatable reciprocable shaft coaxial with the clock operated shaft, a sleeve rotatable upon the non-rotatable

- shaft, coaxing clutch sections upon the sleeve and clock operated shaft, an arm pivoted to swing in a plane including the part shifted by the governor and the non-rotatable shaft and having a link connection with the non-rotatable shaft, a spring engaging said arm and constantly urging the same toward the part shifted by the governor and in a direction shifting the non-rotatable shaft to engage said clutch sections, a spur carried by the arm and engaging in a socket carried by the part shifted by the governor and an operative connection between the register and said sleeve.
- 15 2. In an indicator of the type described, a shaft adapted to be driven from the element to be timed during the operation thereof, a clock operated shaft, a governor driven from the first named shaft, an element shifted by the governor, means positively limiting the shifting of said element, a non-rotatable shaft coaxial with the clock operated shaft having a rotatable clutch section coaxing with a clutch section carried by the clock shaft, means constantly urging said clutch sections into engagement
- 5 and an operative connection between the clutch section and the governor preventing engagement of the clutch sections when the governor is at rest and counter mechanism 30 operatively connected with the first named clutch section.
3. In a running time indicator, a shaft adapted to be driven from an element to be timed, a clock operated shaft, counter mechanism, coaxing clutch sections one driven from the clock operating shaft and the other operatively connected with the counter mechanism to drive the same and means for moving said clutch sections into and out of 40 engagement including a governor driven from the first named shaft and an operative connection between the governor and the last named clutch section including a part positively limiting such movement to thereby prevent forcible engagement of the clutch sections.

In testimony whereof we hereunto affix our signatures.

CARL S. PASSAMANECK.
HARVEY E. McCALLOU.
